[57] CLAIM

The ornamental design for an electrostatic copying machine, as shown and described.

DESCRIPTION

FIG. 1 is a front elevational view of an electrostatic copying machine showing my new design;

FIG. 2 is a top plan view thereof;

FIG. 3 is a right side elevational view thereof;

FIG. 4 is a left side elevational view thereof;

FIG. 5 is a rear elevational view thereof;

FIG. 6 is a bottom plan view thereof;

FIG. 7 is a right front perspective view thereof;

FIG. 8 is a right front perspective view thereof with the paper feeding and copy holding and receiving trays in place;

FIG. 9 is a front elevational view another embodiment of my new design of FIGS. 1-8;

FIG. 10 is a top plan view thereof;

FIG. 11 is a right side elevational view thereof;

FIG. 12 is a left side elevational view thereof;

FIG. 13 is a rear elevational view thereof;

FIG. 14 is a bottom plan view thereof;

FIG. 15 is a right front perspective view thereof;

FIG. 16 is a right front perspective view thereof with the paper feeding and copy holding and receiving trays in place.

The paper feeding, copy holding, and receiving trays have been omitted in FIGS. 1-7 and 9-15 for ease of illustration and clarity.
